ABSTRACT OF THE DISCLOSURE

A process for the manufacture of screened colored positive direct-viewing images, which in the printing industry permit the rapid detection of the matching of the component print positives which the final printed product will show is disclosed.

The present invention relates to a process for the manufacture of screened colored positive direct-viewing images, which in the printing industry permit the rapid detection of the matching of the component print positives which the final printed product will show. The color shades of the base colors yellow, magenta and cyan are so controlled by the copying process that they are matched to the printing inks.

The proof printing of a photolithographic print is even today still a time-consuming and expensive matter. Various attempts have already been made to produce proof prints of correct color and correct tone values more rapidly and more cheaply, avoiding the customary proof printing approach. Hitherto, however, the methods are too expensive, or the results are not satisfactory.

Particular problems arise in the production of so-called "color proofs" on photographic multi-color material, because in the graphic industry a "proofing system" has to provide variability of the base color shades and color densities.

A process has now been discovered which fulfils this requirement and yields images which come very close to the printed product.

The subject of the invention is, accordingly, a process for the manufacture of a screened, photographic color copy simulating a multi-color print, preferably multi-color offset print, in which the screened positive color separation components of the original, which appertain to the individual colors, are exposed together with the screened black separation component and, if appropriate, the black separation component alone is additionally exposed onto a light-sensitive positively working color-photographic material, characterized in that (a) at least one of the color separation components together with (b) the black separation component and (c) at least partially together with at least one of the remaining color separation components, is exposed with the light of the color appertaining to the color separation component (a) onto the light-sensitive color-photographic material, and the material thus exposed is processed to give a screened, positive direct-viewing image which possesses base colors matching the printing inks.

In the process according to the invention the procedure is thus that the screened, positive color separation components of the original (blue=B, green=G, red=R) and the black separation component (black=S) of the original are brought into register with one another as combina-

2

tions BS, GS and RS, and are then successively exposed, in optional sequence, with the corresponding filters (blue=b, green=g, red=r) onto a light-sensitive, positively working photographic material in the combinations BS-b, GS-g, RS-r and, if appropriate, additionally S alone, the improved matching of the color impression of the color copy to the printing inks being achieved in that additionally, at least one of the following combinations is exposed: BGS-b, BGS-g, BRS-b, BRS-r, GRS-g, GRS-r, BPRS-b, BGRS-g or BGRS-r.

The exposures, without and with a 2nd and optionally 3rd color separation component (c) are computed from the densitometric measurement of the printing ink and from the colors on the photographic copy.

In the process according to the invention, the procedure followed is thus that, depending on the measured color deviation of the individual base colors of the "color proof" from the printing ink, a second and, if appropriate, a third color separation screened positive is exposed to a greater or lesser extent together with the color separation positive to be copied, and that this is done in such a way that the proportion of exposure of the additional second or third color separation component with the main color separation component is together as a rule 10 to 100%, preferably 40 to 80%, of the total exposure time of the first color separation component.

The second possibility of adapting the "proof" to the printing conditions is, in addition to varying the color shades, adjusting the maximum densities of the individual base colors, or reduction, to the print color density. For this purpose, an exposure through the black print positive is made with the color filter complementary to the reducing color. The exposed material is subsequently developed to give a positive direct-viewing image.

The process according to the invention is above all suitable for simulating screened multicolor offset-printed products.

Photographic material for the silver dye bleach process has proved particularly advantageous for the process according to the invention, since it permits colored images to be produced wherein the colors correspond relatively well to the printing inks. A further advantage of the photographic material for the silver dye bleach process is that it permits positive copies of positive color separation components to be produced with ease. The present process is, however, not restricted to photographic material for the silver dye bleach process, and material used, for example, for the dye development process is also suitable.

The color separation components required for the process according to the invention, for example the green, red and blue filter separation component, as well as the black separation component, are produced in the usual and known manner. Since these separation components are in the form of monochrome, and generally black-and-white, diapositives, the choice of the copying lights in photographic further processing now only depends on the spectral sensitivities of the copying material.

The color separation component positives, which are in most cases black-and-white, correspond to the positives usually employed in screen offset printing technique. These screen positives are as a rule contact copies or enlargements of screened or continuous-tone separation negatives, and in the case of continuous-tone negatives a contact screen must be copied with them. The continuous-tone or screen negatives are produced with color filters,

either conventionally or via so-called "scanners." The color retouching and correction of the color separation components is adapted to the works colour scale of the individual printing works.

For comparison, the printing ink is measured with the photographic "color proof," with and without mixing-in of a 2nd or 3rd color separation component, in a densitometer. The following values are found:

Measuring filter in the densitometer	Relative densities		
	Yellow	Magenta	Cyan
I.....	Blue.....	1.32	0.14
	Green.....	0.85	1.55
	Red.....	0.20	0.57
II.....	Blue.....	1.31	0.18
	Green.....	0.56	1.40
	Red.....	0.28	0.58
III.....	Blue.....	1.31	0.18
	Green.....	0.82	1.50
	Red.....	0.28	0.58

NOTES.—I=Here the printing inks used are measured. II=These are measured values of a "color proof" without mixing-in. III=This represents the chosen subdivision of the exposure to blue light into a part exposure with blue filter positive plus black print positive and a 60% part exposure with blue filter positive plus black print positive plus green filter positive, with the exposure of the combinations green filter positive plus black print positive and red filter positive plus black print positive being unchanged. The exposure times are computed as follows: the exposure to blue light with the blue filter positive and the black print positive is 4 seconds for a correctly exposed image. This exposure is now subdivided into a part exposure of 1.6 seconds (40%) for the blue filter positive and black print positive and 2.4 seconds (60%) for the second part exposure of the blue filter positive, green filter positive and black print positive.

EXAMPLE 1

If a warmer (yellower) magenta printing ink is used, the "color proof" can be adapted to the printing ink by increasing the proportion of yellow in the magenta. The procedure is as follows:

Effective relative exposure times:

- (1) 1.6 seconds
- (2) 2.4 seconds
- (3) 2 seconds
- (4) 2 seconds.

The blue filter positive is combined in register with the black print positive and copied onto the emulsion sensitive to blue, by means of a part exposure with blue light. The green filter positive is then added thereto and the second part exposure effected with blue light. For the green filter exposure, the green filter positive and the black print positive are used, and for the red exposure the red filter positive is again used with the black print positive.

After these exposures, the color-photographic material is developed by the silver dye bleach process to give a positive direct-viewing image, which comes close to the printed product produced with the same separation components.

25

If warmer magenta and cyan printing inks are used, the procedure for adapting the "color proof" is as follows:

Effective relative exposure times:

- (1) 1.6 seconds
- (2) 2.4 seconds
- (3) 4 seconds
- (4) 4 seconds.

As in Example 1, there are 2 exposures using the blue filter onto a photographic material for the silver dye bleach process:

The first with the blue filter and black print positive and the second exposure additionally with the green filter positive and red filter positive. The green and red exposures remain the same as in Example 1. After the exposures, a positive direct-viewing image is obtained, which comes close to the printed product produced with the same separation components.

Relative density values measured as in Example 1:

Measuring filter in the densitometer	Relative densities		
	Yellow	Magenta	Cyan
Blue.....	1.32	0.14	0.02
Green.....	0.85	1.55	0.26
Red.....	0.37	0.58	1.45
Blue.....	1.31	0.18	0.02
Green.....	0.82	1.50	0.31
Red.....	0.40	0.61	1.48

For comparison, the printing ink is measured with the photographic "color proof," with and without mixing-in of a 2nd or 3rd color separation component, in a densitometer. The following values are found:

The blue exposure is again subdivided into 40% exposure for the first part exposure of the blue filter positive and black print positive at 60% exposure for the second part exposure, in which blue filter, green filter and red filter positives and the black print positive are used. In this way yellow is mixed into the magenta and cyan color of the "color proof."

As regards the density values it should be mentioned that a trained eye can detect a difference of about 0.03 density unit.

EXAMPLE 3

Instead of the customary cyan color shade, a reddish cyan is desired, in which additionally the maximum density of the cyan layer must also be reduced. The procedure is here as follows:

Effective exposure times:

- (1) 4 seconds
- (2) 3 seconds
- (3) 1 second
- (4) 4 seconds
- (5) .05 second.

Step 5 reduces the maximum density of the cyan layer.

The screened separation component positives of an original color image are copied onto a photographic material for the silver dye bleach process in the same way as described in Example 1. The exposure times of the part exposure depend again on the desired percentage mixing

of one base color into the other base color. Equally, the exposure to reduce the cyan density depends on the desired change.

These exposures give a positive direct-viewing image which comes close to the printed product produced with the same separation components.

What is claimed is:

1. In a process for the manufacture of a screened, photographic color copy simulating a multi-color print, in which the screened positive color separation components of the original, which appertain to the individual colors, are exposed together with the screened black separation component and, if appropriate, the black separation component alone is additionally exposed onto a light-sensitive positively working silver dye bleach color-photographic material, the improvement which comprises exposing at least one of the color separation components (i) together with the black separation component and at least partially together with at least one of the remaining color separation components (ii) with the light of the color appertaining to the color separation component (i) onto the light-sensitive silver dye bleach color-photographic material, and processing the material thus exposed to give a screened, positive direct-viewing image which possesses base colors matching the printing inks.
2. Process according to claim 1, which comprises co-exposing the second color separation component (ii) for 10 to 100% of the total exposure time of the color separation component (i).
3. Process according to claim 2, which comprises co-exposing the second color separation component (ii) for 40 to 80% of the total exposure time of the color separation component (i).
4. Process according to claim 3, which comprises simulating with the photographic color copy a multi-color planographic printing product.
